UNITED STATES PATENT OFFICE

JOHN N. GEORGAS, OF GARY, INDIANA

PAINTING APPARATUS

Application filed April 27, 1929. Serial No. 358,615.

This invention relates to certain novel improvements in painting apparatus and has for its principal object the provision of an improved construction of this character which will be highly efficient in use and economical in manufacture.

It is among the objects of my invention to provide a painting apparatus which will include a revolving brush which will apply paint or the like to surfaces over which the device is moved.

Another object of the invention is to provide a device for supplying paint to the revolving brush.

A still further object of the invention is to provide a removable container in which the paint to be supplied to the brush may be arranged.

Still another object of the invention is to provide an arrangement for supporting the means for supplying paint to the brush in the tank or container in which the paint is mounted.

A further object of the invention is to provide an arrangement for supporting the brush and a portion of the paint supplying means in a manner which will permit expeditious removal thereof when so desired.

A still further object of the invention is to provide a novel driving means for operating the brush which will embody an arrangement whereby the brush may be rotated in opposite directions and to arrange the means for controlling the direction of rotation in a position such that access thereto may be readily attained.

A still further object of the invention is to provide a means for supplying power to the device and to arrange this means so that it may be expeditiously transported.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a side elevational view of a pre-

ferred form of construction for my invention;

Fig. 2 is a front elevational view of the device as depicted in Fig. 1;

Fig. 3 is a sectional view taken substantially on the line 3—3 on Fig. 2;

Fig. 4 is a sectional detail view depicting the arrangement employed for mounting the brush in position;

Fig. 5 is a sectional view taken substantially on the line 5—5 on Fig. 3;

Fig. 6 is a sectional view taken substantially on the line 6—6 on Fig. 3;

Fig. 7 is a sectional view taken substantially on the line 7—7 on Fig. 3;

Fig. 8 is a sectional detail view taken on a horizontal plane with respect to the device depicting a portion of the parts shown in Fig. 5; and

Fig. 9 is a sectional view taken substantially on the line 9—9 on Fig. 4.

In the accompanying drawings wherein I have illustrated a preferred form of construction for my invention 10 indicates the main housing of my device which is preferably formed in a shape substantially similar to that depicted in the drawings. Arranged at the ends of the main housing 10 are cap portions 11 and 12 which define compartments between the ends 13 and 14 of the housing 10 and said cap portions. In the housing 10 two compartments are defined which are indicated by 15 and 16.

The compartment 16 is arranged in a manner such that it embodies an open front side indicated by 17. Arranged in the compartment 16 is a container 18 in which the paint or the like to be spread by the device is intended to be mounted. The container 18 is retained between the upper wall 19 of the compartment 16 and a rod 20 which fits into a co-operating recess 21 formed in the lower end of the paint container 18 and it is, therefore, manifest that the paint container 18 is clamped between the wall 19 and the rod 20.

Brackets such as 22 are positioned interiorly of the container 18 adjacent each end thereof and arms 23 are pivotally connected to the brackets 22 adjacent the inwardly dis-

posed ends thereof. A roller 24 extends across the container 18 and is rotatably journaled in the arms 23. Rollers 25 and 26 extend across the container 18 and are rotatably mounted in the arms 23. Another roller 27 is supported by the arms 23 in a manner to be set forth hereinafter and extends across the container 18 adjacent the upper end thereof and a portion of this roller 27 extends through an opening 28 in the container 18. A member 29 in the form of an endless belt extends around the rollers 27, 26, 25, and 24 in the manner clearly illustrated in Fig. 3 and it is, therefore, apparent that this belt 29 like member 29 is in contact with the paint in the container 18 and the portion of this belt-like member 29 that extends around the portion of the roller that extends through the opening 28 is employed to supply paint 20 to the revolving brush to be set forth hereinafter and this belt 29 is caused to travel over the rollers.

It is apparent that the container 18 includes a wall portion 30 which extends thereacross toward the opening 28 in a manner so as to define an open space below the wall 19 in the compartment 18. In this open space the paint spreading member or brush 31 is arranged and the brush 31 is disposed so that a portion thereof extends out through the opening 17 beyond the walls of the housing 10 and this portion of the brush so extended acts to spread the paint on the surface over which the device is moved. In the present instance the brush 31 is shown as embodying a shaft 32 on which an elongated drum 33 is arranged. Arranged on the periphery of the drum 33 in a spiral formation are bristles 34 and the disposition 40 of these bristles is best illustrated in Fig. 2. The brush 31 is revolved in the manner to be set forth. The bristles 34 engage the portion of the belt 29 extended through the opening 28 and collect paint therefrom and after these bristles move into the position extended through the opening 17 these bristles will supply paint to the surface in contact therewith.

The brush 31 is mounted in the following manner so as to be readily removable. By referring to Fig. 4 it may be seen that an opening 35 is provided in the end wall 14 in which a bushing 36 is arranged. A stud 37 extends through the opening in the bushing 36 and on the end of the stud 37 arranged interiorly of the wall 14 an enlarged head 38 is provided. A diametrically extending groove 39 is provided in the face of the head 38 disposed toward the brush structure 31. On the end of the shaft 32 supporting the drum 33 a diametrically extending lug 40 is provided which is of a shape substantially similar to the shape of the groove 39 and this lug is intended to be disposed in the groove 39. In the periphery of the en-

larged head 38 a notch 41 is formed. A member 42 is disposed in the notch 41 and is formed so as to be substantially ring shaped and has a stem portion 43 extending from one end thereof while the opposite end terminates adjacent the interconnection of this stem portion. When the member 42 is disposed in position in the recess 41 the lug 40 is held against displacement from the notch 39. A similar arrangement is provided for supporting the opposite end of the brush from the wall 13. Further, by removing the members 42 from the recesses 41 the lugs 40 may be slid from the notches 39 and in this manner the brush 31 may be removed when so desired. On the portion of the stud 37 extending exteriorly of the wall 14 interiorly of the cap 12 a pulley 62 is arranged and the utility of this pulley will be described more fully hereinafter.

An arrangement substantially similar to that set forth is associated with the ends of the roller 27 so as to mount this roller in position and this arrangement obviously facilitates the removal of said roller 27.

The mechanism as thus far described is assembled in the following manner. The first portion of the mechanism to be installed will be the insertion of the arms 22 and 23 into the container 18. After these arms and the rollers carried thereby have been inserted in said container the roller 27 is arranged in position with the belt 29 extending therearound. The container 18 is then arranged between the wall 19 and the rod 20. After this has been carried out the brush 31 is arranged in position. It is manifest that the paint in the container 18 will be supplied to the brush 31 by the belt like member 29 as these mechanisms are rotated and the arrangement for rotating these mechanisms will now be described.

By referring to Fig. 5 it may be seen that a shaft 44 extends across the compartment 15 and is journaled in the walls 13 and 14. Arranged so as to be freely rotatable on the shaft 44 are worm wheels 45 and 46 which are held against endwise movement in any approved manner as by the collars 47. The worm wheels 45 and 46 are spaced apart as clearly illustrated in Fig. 5 and arranged intermediate these worm wheels is a clutch structure generically indicated by 48. The clutch structure 48 is keyed to the shaft 44 so as to be rotatable therewith but slidable axially thereof. This clutch structure 48 includes clutch faces 49 and 50. On the face of the clutch face 49 disposed toward the worm wheel 46 a clutching substance 51 such as cork or brake lining material is arranged and a similar material 52 is arranged on the adjacent face of the worm wheel 46 and this section of material engages the section 51 when the clutch face 49 is moved toward and into engagement with the adjacent face of

the worm wheel 46. A similar arrangement is provided on the adjacent faces of the clutch 50 and the worm wheel 45. The clutch member 48 includes a collar structure 53 which has a groove 54 provided therein. Disposed in the groove 54 is the lower end portion of a shifting member 55 and this lower end portion 56 is substantially U-shaped as illustrated in Fig. 3. The shifting member 55 is fixed to a shaft 57 that is journaled in opposite walls of the housing 10 defining the compartment 15 and this is clearly illustrated in Fig. 3. By manipulating the shifting member 55 the clutch structure 48 may be moved so as to bring about engagement of either the clutch face 50 with the worm wheel 45 or the clutch face 49 with the worm wheel 46.

On the ends of the shaft 44 extending beyond the walls 13 and 14 are pulleys 58 and 59. A belt 60 (Fig. 3) extends around the pulley 58 and the pulley 61 mounted on the supporting mechanism on the adjacent end of the roller 27 and the pulley 62 mounted on the stud 37. The belt 60 is of the so called endless type. The clutch arrangement on the shaft 44 is such that it will rotate said shaft in opposite directions and, therefore, when the clutch face 50 and the worm wheel 45 are engaged the shaft 44 will be rotated in one direction and movement will be imparted through the belt 60 to operate the roller 27 and the brush 31 in the manner set forth. Also when the clutch face 49 and the worm wheel 46 are engaged the shaft will be rotated in the direction opposite to that set forth and movement will, in this instance, be transmitted through the belt 60 to the roller 27 and brush 31 to rotate these members in the opposite direction. A belt 63 substantially similar to the belt 60 and connected in a similar manner is arranged at the opposite end of the device and co-operates with the pulley 59 on the shaft 44. In order to operate the shaft 44 and the worm wheels 45 and 46 I provide the following mechanisms.

Shafts 64, and 65 are journaled in the walls defining the compartment 15 and extend parallel to the shaft 57. Worm gears 66 and 67 are mounted on these shafts and the leads of these worm gears extend in opposite directions. The worm wheel 45 which meshes with the worm gear 66 is arranged so as to have the lead thereof corresponding to the lead of the worm gear 66 and the worm wheel 46 is correspondingly related to the worm gear 67. The shaft 64 is extended out through the outwardly disposed wall of the compartment 15 and a flexible shaft 68 of approved form is connected to this portion of the shaft 64. The flexible shaft 68 is also connected to the shaft 69 of a motor 70. A suitable supporting strap 71 is connected to the motor 70 and this sup-

porting strap is arranged about the body of the operator of the mechanism in order that the motor will be supported adjacent the machine. On the shaft 64 a pulley 72 is arranged and aligned with the pulley 72 is 70 a pulley 73 on the shaft 65 and a belt 74 extends between these pulleys and in this manner movement imparted to the shaft 64 is transmitted to the shaft 65.

As is best illustrated in Fig. 1 the portions of the housing 10 co-operating to define the compartment 15 extend outwardly with respect to the portions defining the compartment 16. A handle 75 extends upwardly from this outwardly extending portion defining the compartment 15 and a bracket 76 extends between the upper end of the handle 75 and the wall 19. This handle 75 is arranged substantially midway between the walls 13 and 14 and it is, therefore, apparent that the device may be expeditiously manipulated when this handle 75 is properly gripped. The clutch operating member 55 extends upwardly in the manner illustrated in Fig. 3 and the upper end thereof is extended through a slot in the bracket 76. In the bracket 76 three depressions 77 are formed and a lug 78 on the upper end portion 79 of the operating member 55 is selectively fitted into these recesses. When the lug 78 is disposed in the intermediate of the recesses 77 the roller 53 is arranged in an intermediate position. When the lug 78 is disposed in the recess 77 positioned toward the right as viewed in Fig. 6 the clutch face 49 will be engaged with the worm wheel 46 and when the lug 78 is disposed in the left of the recesses 77 the clutch face 50 will be engaged with the worm wheel 45.

In use the paint container 18 is arranged in the device as set forth and the motor 70 is set in operation and movement is transmitted through the flexible shaft 68 to the shaft 64 and thence through the belt 74 to the shaft 65. The device is gripped by the handle 75 and as the device is moved downwardly the mechanisms are arranged so as to rotate the brush 31 upwardly. Paint is supplied to the brush 31 in the manner set forth and it is apparent that since the brush 31 rotates in a direction opposite to the direction of movement of the device the paint will be very effectively spread on the surface over which the device is moved. As the device is moved in the opposite direction the brush 31 is caused to rotate in a direction opposite to that set forth and, therefore, again the paint will be very effectively spread over the surface. This device may be used to coat either curved or flat surfaces which may be arranged in either vertical or horizontal planes or planes intermediate these vertical or horizontal planes.

While I have illustrated and described the preferred form of construction for carrying

my invention into effect, this is capable of variation and modification, without departing from the spirit of the invention. I, therefore, do not wsh to be limited to the 5 precise details of construction set forth, but desire to avail myself of such variations and modifications as come within the scope of the appended claims.

Having thus described my invention what 10 I claim as new and desire to protect by Letters Patent is:

1. In a device of the character stated, a housing having compartments therein, a container, means for supporting said container in one of said compartments, a brush in said compartment having said container therein, means for supporting said brush, means for supplying material in said container to said brush, means for operating said brush and said material supplying means, said last named means including motive power means, means in another of the compartments in said housing for controlling the operation of said operating means, said last named means including oppositely rotating members, and means for connecting said operating means to either of said rotating members to cause rotation of said brush and supplying means in opposite directions.
2. In a device of the character stated, a housing having compartments therein, a container, means for supporting said container in one of said compartments, a brush in said compartment having said container therein, means for supporting said brush, means for supplying material in said container to said brush, means for operating said brush and said material supplying means, said last named means including motive power means, means in another of the compartments in said housing for controlling the operation of said operating means, said last named means including oppositely rotating members, means for connecting said operating means to either of said rotating members to cause rotation of said brush and supplying means in opposite directions, said housing having a handle thereon, and means associated with said handle for operating said connecting means.

In testimony whereof I affix my signature.
JOHN N. GEORGAS.
